UNITED STATES PATENT OFFICE.

HENRY ALLENDER, OF DETROIT, MICHIGAN.

MACHINE-GUN.

SPECIFICATION forming part of Letters Patent No. 372,191, dated October 25, 1887.

Application filed April 1, 1887. Serial No. 233,329. (No model.)

To all whom it may concern:

Be it known that I, HENRY ALLENDER, of Detroit, in the county of Wayne and State of Michigan, have invented a new and useful Improvement in Machine-Guns, of which the following is a specification.

My invention consists in a machine gun the main principle of which is the use of semi-chambers, whereby the reciprocating motion necessary to insert a fresh cartridge and extract the shell is entirely dispensed with.

Figure 1 is a perspective of the complete gun. Fig. 2 is a rear elevation of the gun. Fig. 3 is a plan view, with the upper half of the case removed. Fig. 4 is a rear elevation of the two chamber-shafts. Fig. 5 is a cross-section on the line $x-x$, Fig. 1. Fig. 6 is an end view, and Fig. 7 an elevation, of one of the semi-chambers.

1 represents the case of the gun, made of metal, oval in form externally, and internally formed into two cylinders, each of which opens into a vertical slot, 2, cut through both parts of the case, as clearly shown in Fig. 5. The two parts of the case are provided with flanges 13, to receive bolts or screws 12, by which the case is held together. On the rear end of the case is a flange in which are formed the two boxes 8 and 9, to form bearings for the shafts, and on the front of the case is a flange in which are formed boxes 22 23 for the front journals of the shaft, while into said flange, between said boxes, is screwed the end of a barrel, 7, as clearly shown in Fig. 3.

4 4 represent two shafts, each of which is scalloped with an equal number of longitudinal grooves, there being six in each shaft, as illustrated in the drawings, though this number may be greater or less. The right-hand shaft 4, Fig. 3, is journaled at the front end in box 23 and at its rear end in box 9, and carries at the rear end of its journal a ratchet-wheel, 17, in which are as many teeth 27 as there are longitudinal grooves in the shaft.

45 The left-hand shaft 4, Fig. 3, is journaled at its front end in box 22 and at its rear end in box 8, and is extended beyond said box, as shown at 18, to receive a crank, 14, by which motion is communicated to said shaft. The 50 rear end of the left-hand shaft 4, within the

case, is enlarged and provided on its outer edge with a number of circular projections, 24, equal in number and opposite to the longitudinal grooves in said shaft, in each of which projections is set a firing-pin, 25, capable of longitudinal motion, as is clearly shown in Fig. 4, in which the dotted lines represent the grooved shaft. The rear end of the right-hand shaft, within the case, is made of such form as to mesh with the opposing portion of the left-hand shaft, as just described, and as clearly shown in Fig. 4, whereby rotation of the left-hand shaft 4 causes similar rotation in opposite direction of the right-hand shaft, the projections 24 on the left-hand shaft meshing with the depressions 26 in the right-hand shaft.

3 represents a semi-cartridge-chamber, having at one end an annular groove, 6, to receive the rim of a cartridge, and having its edges cut on the same circle as shaft 4. The semi-chambers 3 are made to fit the longitudinal grooves in the shafts 4 and to turn with said shafts in the case, always presenting their open sides to the periphery of the shaft on which they are carried.

19 represents a firing-pin in line with the center of barrel 7, carried in the flange at the rear of the case, and adapted to register with each of the firing-pins 25 as said pins come opposite the center of the barrel.

15 represents a hammer, pivoted at 11 in a lug, 10, formed on box 9, and its end extends over firing-pin 19.

16 represents a cam on the inner side of hammer 15, which comes in contact with the teeth on ratchet-wheel 17 when said wheel is rotated, whereby the hammer is actuated.

20 represents a spring secured to the case at 21 21, passing under the short end of hammer 15 and adapted to press the other end of said hammer toward firing-pin 19. I have shown this spring in the form of a horseshoe; but its form is immaterial, as its office is simply to throw the hammer against the firing-pin.

The operation of my invention is as follows: A cartridge being dropped into slot 2 in the upper half of case 1, with the bullet toward the barrel 7, will fall through said slot until it rests against and is supported by the periphery 95 100

of shafts 4. On rotating these shafts by means of crank 14 the two semi-chambers 3 which are nearest said slot 2 will approach each other, and as the edge of the cavities in said chambers meet, the cartridge will drop into said cavities, and by the further rotation of said shafts a complete closed chamber will be formed, as shown at 5, within which will be the cartridge. As the shafts have rotated, one of the teeth 27 on ratchet-wheel 17 will have raised cam 16 so as to lift the hammer 15 against the action of spring 20, and at the instant the two opposing semi-chambers 3 form a complete chamber the hammer 15 will be released, will strike the end of firing-pin 19, will drive the pin against the firing-pin 25, which is in line with the complete chamber then formed, and the firing-pin will explode the cap in the cartridge, and thus fire the gun. The further rotation of the shafts 4 causes the semi-chamber 3, containing the exploded cartridge-shell, to separate, and the shell will either fall out through the slot 2 in the lower half of the case, or, if it sticks in one of the semi-chambers, will be removed therefrom by the edge of said slot 2 and will fall out of the gun. By feeding the cartridges in any convenient manner to the slot 2 in the upper half of the case, the action of the pin will be continuous so long as the supply of cartridges is kept up and the rotation of the shaft 4 continues.

I have made the drawings accompanying this application showing the semi-chambers 3 as made separate from the shafts 4 and inserted in said shafts. It is obvious, however, that said semi-chambers may be formed directly in said shafts, if desired.

What I claim as my invention, and desire to secure by Letters Patent, is—

1. A machine-gun having two rotary shafts, 40 each carrying on its periphery a series of semi-chambers adapted to register with each other, a wheel on one of said shafts carrying a number of circular projections corresponding with the semi-chambers therein, and having in each 45 projection a firing-pin opposite the center of said semi-chamber, a wheel on the other of said shafts having depressions adapted to mesh with said projections, a vertical slot through the case of the gun above the meeting-point of 50 said shafts, a barrel fastened to the forward end of the case in line with the meeting-point of said shafts, means for rotating said shafts, a firing-pin located in the rear end of said case in line with this meeting-point of said shafts, 55 and a hammer actuated by the rotation of said shafts and adapted to act on said firing-pin, substantially as shown and described.

2. In a breech-loading gun, a case having two rotary shafts journaled therein, each having in its periphery one or more semi-cartridge-chambers, a gear-wheel on one shaft, having projections adapted to form a breech for each cartridge-chamber and having a firing-pin in each projection, and a gear-wheel on the outer 65 shaft, having depressions adapted to mesh with said projections, substantially as shown and described.

HENRY ALLENDER.
